UNITED STATES PATENT OFFICE.

CHARLES JOHN COOKE, OF HONGKONG, CHINA.

FIREARM.

1,229,721.

Specification of Letters Patent. Patented June 12, 1917.

Application filed February 17, 1917. Serial No. 149,234.

To all whom it may concern:

Be it known that I, CHARLES JOHN COOKE, a subject of the King of Great Britain, residing at Hongkong, China, have invented 5 certain new and useful Improvements in Firearms; and I do hereby declare the following to be a full, clear, and exact description of the invention, such as will enable others skilled in the art to which it 10 appertains to make and use the same.

My present invention relates to fire-arms, but more particularly stated it relates to small arms of the rapid-fire or magazine type, as also to novel and improved means 15 for mounting recharging and manipulating the same.

It comprises a suitable magazine-pistol, that of the accompanying illustrations for example, being the well known Colt automatic forty-five caliber type, in conjunction 20 with a mount for same of novel construction.

The present invention has for its primary object a material increase in the repeating 25 capacity of automatic firearms of the character indicated.

A further object is the production of extremely simple, accurate and reliable means for effecting such increased efficiency including 30 a readily attachable support for said arm or magazine-holder for spare magazines.

A further object is the production of magazine firearms equipped with a magazine 35 holder for standard magazines, and a bayonet attachment for use in modern trench warfare or other close quarters.

As a further object the invention contemplates the production of firearms of the 40 character indicated, and a specially constructed support therefor and holder for spare magazines, combined and arranged to coöperate with a marked degree of efficiency in the performance of their intended functions, and under all conditions of comparatively close quarter conflicts; a repeating arm wherein the number of successive shots is limited only by length of the magazine-holder and the number of magazines contained 45 therein; an implement of warfare which may instantly be reversed and effectively utilized as a bayonet in repelling charges; and one which adds but little additional weight to the accoutrements of an 50 infantryman.

A further object of the invention is the production of coöoperative means whereby exhausted magazines may be instantly ejected from firing position within the arm, and as quickly replaced by fully charged 60 magazines fed successively in alinement from an attached magazine-holder directly into firing position.

With the foregoing and other objects and advantages in view the present invention 65 will be hereinafter more particularly described, and then pointed out in the appended claims.

In the accompanying drawings which form part of this application for Letters 70 Patent, and whereon like numerals indicate corresponding parts in the several views:

Figure 1 is a side elevation of my invention completely assembled and ready for service. 75

Fig. 2 is a front elevation of parts shown by Fig. 1, looking directly into magazine-holder and muzzle of the arm.

Fig. 3 is a detached detail view in perspective of a form of clamp for detachably 80 securing parts of my invention together.

Fig. 4 is a longitudinal central section taken through the magazine-holder upon a relatively enlarged scale.

Fig. 5 is a front elevation of parts shown 85 by Fig. 4.

Fig. 6 is a transverse sectional view taken on the line 6—6 of Fig. 4.

Fig. 7 is also a transverse section taken on the line 7—7 of Fig. 4, and, 90

Figs. 8 and 9 are fragmentary views in side and rear elevation respectively, both partly broken away showing one modification of means for detachably connecting a firearm and a support therefor or magazine holder for spare magazines. 95

Reference being had to the drawings and numerals thereon, 10 indicates a magazine firearm which may be of any approved construction, the present drawings showing, for example, an ordinary Colt automatic, in the handle of which there is an open ended magazine-chamber 11 communicating above with the firing chamber of the arm, and adapted to receive and removably retain an ordinary magazine in the well understood manner. 100

The numeral 12 indicates a support for the arm comprising a magazine-holder, for a plurality of recharging or spare magazines 110

13, the said holder being preferably made of hard wood and channeled from end to end as at 14, to produce a magazine chamber, the same being adapted and arranged to receive 5 a plurality of ordinary magazines 13 in contact and in stacked alinement, allowance being made for a free movement thereof longitudinally within said channel or chamber 14.

The front edges of the magazine chamber 10 14 throughout the major portion thereof, are slightly overhung by longitudinal flanges 15, 15 for confining and preventing removal of magazines 13 in a lateral direction, while at intervals, within one side of the support 15 12, are positioned spring-pressed friction shoes 16, for bearing gently upon one side of each magazine 13 within the said chambered support to prevent rattling or accidental movement of the magazines. These shoes 20 may be of any convenient material and introduced in any approved manner, the plan shown contemplating pockets 17 opening through one side of the support 12, leaf-springs 18 secured within said pockets having at their free ends the shoes 16 aforesaid, and closure plates 19 as shown in section by 25 Fig. 5 of the drawings.

The bottom of the magazine chamber 14, at a point above the upper ends of flanges 15, 30 is recessed or pocketed as at 20, and within this pocket, as best shown by Fig. 4, is pivotally mounted a tripping block 21, spring-pressed as at 22 so as to keep its upper end normally projecting a slight distance into 35 the channel or magazine chamber 14. The said block 21 may, of course, be spring-pressed in a variety of ways, in that shown, however, the spring 22 is a coil spring surrounding a guide pin 23 projecting from a 40 back plate 24, and headed at its innermost end as at 25, to limit the forward movement of the tripping block, and the said back plate 24 is provided with a projecting eye 26 as a convenient means of affixing a periscope 45 attachment (not shown).

Immediately above the said back plate 24 there is firmly secured to support 12 the relatively fixed member 27 of a forcipiform clamp curved to fit the exterior of said support, and at a point above its median line flanged inwardly at 28, as best shown by Fig. 6, thereby materially stiffening the member 27, and leaving a free passage 29 for magazines in their passage to and from the magazine chamber of the arm. Pivotal connected as at 30, there is a relatively movable clamping member 31, also curved to conform to the exterior of the handle of the arm 10, and extending rearwardly and 55 downwardly past its pivotal support the said member 31 terminates in a link or loop 32 resting back of the fixed clamp member 27. Projecting from the last named member there is a screw 33 which passes loosely 60 through an aperture at the center of loop 65

or link 32, and upon this is threaded a clamping nut 34 having for its purpose to close and firmly retain the jaws of the aforesaid forcipiform clamp closed upon the handle of the firearm 10.

At its opposite or lowermost end the support 12 is capped by a metal ferrule or sheath 35 from which projects a stud 36, and also a clip 37 of ordinary and well-known form, for purposes of detachably securing a bayonet 38, as best shown by Figs. 1 and 2.

The foregoing being a description of my present invention in its preferred form of construction, it should be understood that I 70 by no means consider myself restricted to the particular form and arrangement of parts shown and described. On the contrary the invention is capable of a variety of changes and modifications clearly within its 75 scope and meaning and covered by the following claims.

For example, the support and magazine-holder 12 may be of any preferred or convenient length thus providing for an increased number of magazines 13, and an increased reach of the bayonet 38. Moreover, one of various additional means for detachably securing the arm 10 to its support 12 is indicated by Figs. 8 and 9 of the drawings 80 90 wherein forging 39 conforming to the back of the support 12 is flanged as at 40 above, thus forming a grooved slideway open at both ends and extending from back to front of the support, the same being perforated as at 100 41 to permit passage of magazines 13 therethrough. In this form of attachment also laterally extending, parallel and oppositely disposed flanges 42, 42, are affixed to the arm 10 as parts of the side plates 43, 43, 105 inserted beneath the stocks of the handle of the arm, being there retained by agency of the ordinary stock screws, as shown.

The operation of the latter form of attachment or coupling is quite obvious, the 110 flanges 42, 42 being introduced into the open track or slideway 40 are advanced until arrested by engagement of the ordinary lanyard staple or loop 44 at the back of the arm engaging the back of flange 28', whereupon 115 the magazine chambers 11 and 14 are in exact alinement. At this time button 45 is turned to the position indicated by Fig. 9 and held in such locked position by a turn of the wing-nut 46, the parts being then in 120 assembled and operative position.

The operation of the invention as illustrated by Figs. 1 to 7, inclusive, is also quite obvious, but may be briefly outlined as follows:

The firearm and its support being properly assembled as shown by Figs. 1 and 2, with one fully charged magazine 13 in the magazine chamber 11, an operator grasping the handle of the arm in the ordinary man- 130

ner may now automatically empty the contents of said magazine through the firing chamber of the arm in the usual and well understood way.

5 This accomplished, the operator thereupon depresses the usual magazine catch 47 thus releasing the empty magazine which is forced out of its chamber 11 by action of its within contained feeding spring, downwardly into the chamber 14 until arrested by the tripping block 21, as shown in dotted lines by Fig. 4, and ejected.

15 The operator thereupon grasps the usual projecting lip at the bottom of the uppermost of spare magazines 13, instantly elevating the same through the magazine chamber 14 of the support and holder 12, past its tripping block 21, and directly into the open chamber 11 of the arm proper, there to replace the magazine just exhausted and ejected.

20 This process is repeated so long as there are spare magazines within the chamber 14, the walls of said chamber being in direct 25 alinement with those of the magazine chamber 11, and serving thus to instantly and accurately guide charged magazines 13 successively into firing position.

25 Obviously the number and length of magazines 13 is largely a matter of choice and individual requirements. They may be long or they may be short, many or few. The present illustrations show magazines of standard length and capacity, but it may be noted that a most convenient adaptation of 30 this feature of invention is to be found in magazines of slightly greater length, which not only increases their capacity but at the same time facilitates introduction and removal thereof from the magazine chamber 11.

35 After all magazines have been thus exhausted, if there be no opportunity to replace them with fully loaded ones, it is quite obvious that the operator is far from helpless if equipped with my invention, in that he may instantly reverse the weapon and make full use of the bayonet 38 so long as there may be occasion to do so.

40 Having thus described my invention, what I claim and desire to secure by Letters Patent is:

45 1. A firearm provided with a magazine chamber, in combination with a support for said arm also provided with a magazine chamber communicating directly with the first mentioned chamber whereby magazines may be guided in their passage from one to the other of said chambers.

50 2. A firearm provided with a magazine chamber, in combination with a support for said arm also provided with a magazine chamber communicating directly with the first mentioned chamber and of corresponding cross sectional interior dimensions,

whereby magazines may be guided in their passage from one to the other of said chambers.

3. A firearm provided with a magazine chamber, in combination with a support for 70 said arm also provided with a magazine chamber communicating and in longitudinal alinement with the first mentioned chamber whereby magazines may be guided in their passage from one to the other of said chambers. 75

4. A firearm provided with a magazine chamber, in combination with a support for said arm also provided with a magazine chamber capable of receiving a plurality of 80 magazines in stacked relation and guiding them in their passage from one to the other of said chambers.

5. A firearm provided with a magazine chamber, in combination with a support for 85 said arm also provided with a magazine chamber capable of receiving a plurality of magazines in contact and stacked alinement whereby they may be guided in their passage from one to the other of said chambers. 90

6. A firearm provided with a magazine chamber, in combination with a support for said arm also provided with a magazine chamber whereby magazines may be guided in their passage from one to the other of 95 said chambers, and means for detachably connecting said firearm and support.

7. A firearm provided with a magazine chamber in its handle, in combination with a support for said arm also provided with a magazine chamber communicating directly with the first named chamber and adapted to contain a plurality of spare magazines in alinement, and means for successively advancing said magazines into firing position within the first named chamber. 105

8. A firearm provided with a magazine chamber, in combination with a support for said arm also provided with a longitudinally arranged magazine chamber for containing 110 spare magazines in stacked alinement, a tripping block within the last named chamber near the upper end thereof, and means for successively advancing said magazines past said tripping block into the 115 magazine chamber of the arm.

9. A firearm provided with a magazine chamber, in combination with a support for said arm also provided with a longitudinally arranged magazine chamber for containing 120 spare magazines in stacked alinement, and a depressible tripping block within the last named chamber which permits passage of said magazines in an upward direction only into the first named chamber. 125

10. A firearm provided with a magazine chamber, in combination with a detachable support for said arm channeled longitudinally to constitute a guiding receptacle for spare magazines, friction blocks projecting 130

into the last named chamber and bearing upon the magazines contained therein, and means for permitting the passage of said magazines from one of said chambers to the other.

11. A firearm provided with a magazine chamber, in combination with a support for said arm also provided with a magazine chamber whereby magazines may be guided 10 in their passage from one to the other of said chambers, and a forcipiform clamp for securing said arm and support in operative relation.

12. A firearm having a depending handle 15 and a suitable support for said arm, in combination with a clamping member fixed with relation to said support, and a second clamping member pivotally connected with the

first mentioned clamping member and adapted to embrace the handle of the firearm. 20

13. A firearm provided with a magazine chamber in combination with a support for said arm also provided with a magazine chamber communicating directly with the first mentioned chamber whereby magazines 25 may be guided in their passage from one to the other of said chambers, and a bayonet also carried by said support.

In testimony whereof I affix my signature, in presence of two subscribing witnesses.

CHARLES JOHN COOKE.
